FLUID QUANTITY CONTROL

Gordon T. Koehler, Dayton, Ohio, assignor to Koehler Aircraft Products Company, Dayton, Ohio, a corporation of Ohio

Application May 6, 1957, Serial No. 657,100

2 Claims. (Cl. 137—414)

This invention relates to a fluid control apparatus and more particularly to an apparatus utilizing a float controlled valve permitting complete filling of a fluid containing receptacle.

The filling of fuel tanks, for example those of diesel engines, where locomotive engineers insist that the tank be completely filled with no dead space between the fuel level and the upper wall of the tank, commonly results in an estimated average loss of 40 gallons of fuel per filling, this being the amount that can escape with a 20 second overflow. Such escape of fluid results in considerable loss of money and, additionally, introduces fire and working hazards which arise from the spilled fuel.

A principal object of this invention is the provision of an apparatus for use with fluid containing receptacles which provides for complete filling of the receptacle without wasteful overflow.

Another object of this invention is the provision of an apparatus which is readily attached to a fluid containing receptacle to control the quantity of fluid supplied thereto.

Other objects and advantages of this invention will be apparent from the following description, the accompanying drawings and the appended claims.

In the drawings—

Fig. 1 is a sectional view through an apparatus according to the present invention as attached to a fluid containing receptacle and showing the valve partly in elevation;

Fig. 2 is a somewhat enlarged cross sectional view of the control valve taken along the line 2—2 of Fig. 1;

Fig. 3 is an enlarged fragmentary bottom plan view of the control apparatus showing the valve and part of the float operating mechanism;

Fig. 4 is a fragmentary showing of the means connecting the float to the valve;

Fig. 5 is an enlarged fragmentary sectional view of a pilot valve for operating the control valve shown in Fig. 1; and

Fig. 6 is a fragmentary view showing means for venting the float recess chamber.

Referring to the drawings which illustrate a preferred embodiment of the invention, the control apparatus indicated generally by the numeral 10, is secured to the upper portion of a fluid containing receptacle 11 by welds 12.

A housing 15 with an outer end 16 for connection with a fluid supply source and an enlarged inner end 17 defines a fluid conducting passageway 18 for introducing fluid into the containing receptacle 11. Housing 15 is removably attached to containing receptacle 11 by means of bolts 20 which extend through annular flange 21 into a foundation plate 26, this plate in turn being integrally attached to a side and the upper wall of receptacle 11.

The outer end 16 of the housing 15 has internal threads

2

27 adjacent the end thereof to engage the externally threaded end portion 30 of a tube 31 which provides a fluid induction passage into the interior of housing 15. At the opposite end of housing 15, a mounting plate 35 is secured between the enlarged inner end 17 and foundation plate 26 by means of the bolts 20. The mounting plate 35 is isolated from flange 21 and foundation plate 26 by appropriate sealing gaskets 36 which are useful in preventing the escape of fluid from receptacle 11 when it is filled.

A diaphragm-type valve 40 is bolted to the underside of mounting plate 35 by bolts 41 and surrounds an opening 42 which connects the interior of housing 15 with the inlet opening 45 of valve 40. Inlet opening 45 is defined by an annular valve seat 46, the opening being normally closed by a valve seal 47 which is urged against valve seat 46 by coil spring 48. Valve seal 47 is carried on a diaphragm structure 50 which divides the valve into a chamber 51 adjacent inlet opening 45 and a chamber 52 which is isolated from chamber 51 except for a small fluid connecting passage 53 which extends through the center of diaphragm 50. The portion of valve 40 defining chamber 51 is constructed with a plurality of generally radially extending outlet openings 55 which provide for ejection of fluid from chamber 51 when the diaphragm structure 50 has been moved from valve seat 46 thus enabling the entry of fluid from the interior of housing 15 into the interior of the valve.

Diaphragm structure 50 comprises a centrally disposed fitting 60 having an inwardly directed flange 61 which receives a fluid filtering screen 62 to prevent any fluid entrained contaminants from entering fluid connecting passage 53 and clogging it to further fluid passage. A nut-like fitting 65 is threadably engaged to the rear end 30 of fitting 60, and urges the central edge portions of diaphragm plates 66 and diaphragm 67 into tight sealing relationship. The diaphragm 67 is of greater radial extent than the other members comprising the diaphragm structure 50 so that its outer edge can be secured between the upper casing half 68 and the lower casing half 69 to provide a resilient region 70 which enables flexure of the diaphragm structure between open and closed positions.

Connected with the chamber 52 is a pilot valve 71 which controls the accumulated fluid pressure within chamber 52 by either enabling fluid entering the chamber through passage 53 to escape to the interior of the containing receptacle 11 or causing the pressure within chamber 52 to increase by preventing its escape through a passage 72 into the interior of the containing receptacle 11. Controlled flow of fluid through passage 72 of pilot valve 71 is accomplished by a valve member 73 which is pivoted at its lower end to a pivotally mounted actuating arm 74. Thus when valve member 73 is in the position shown in Fig. 5 of the drawings, passage 72 will be closed thereby precluding the escape of fluid from chamber 52 and causing an increase in pressure behind the diaphragm 67.

A pressure relief valve 75 is connected to chamber 52, through fluid passage 76, to provide for the release of pressure from chamber 52 should the pilot valve 71 fail to function properly. Pressure relief 75 comprises a ball 77 which is urged into normal sealing engagement with the outer end of fluid passage 76 by a ball carrier 80 which is biased by spring 81. A pair of outlet passages 82 and 83 provide escape means for fluid escape through fluid passage 76 past ball 77.

A float 85 is attached to the end of a float arm 86 to cause movement of a connecting arm 87 which extends from the lower end of float arm 86 to the lower end of actuating arm 74, where it is adjustably attached by means of nuts 88 and screws 89 to actuating arm 74.

Movement of float 85 in response to a change in the level of fluid within receptacle 11 will result in pivotal movement of actuating arm 74 which will in turn either seat or unseat valve member 73 against the outlet end of passage 72.

A cup-like shield 90 extends upwardly from mounting plate 35 adjacent the opening 25 to define a chamber 91 within the enlarged inner end 17 of housing 15 to provide space to receive float 85 in order that it may move above the maximum fluid level obtainable within receptacle 11. Provision of chamber 91 enables a more complete filling of receptacle 11 than would be the case where the float can move only into contact with the upper wall since the latter arrangement would necessitate interruption of fluid flow at a time when the fluid level was substantially below the top wall of the receptacle. Shield 90 has an opening 92 in the upper wall thereof providing for the removal of gas from chamber 91 so that the liquid level within the tank can rise properly within the float chamber during a filling operation.

A generally U-shaped baffle 95 surrounds float arm 86 and connecting arm 87 to insure proper vertical movement of these parts and to eliminate lateral movement thereof due to the movement of the surrounding fluid medium. Baffle 95 is secured to a larger float housing 96 by bolts 97 which extend upwardly, through openings in mounting tabs 98 of baffle 95, into the lower portion of the housing 96. Baffle 95 includes a plurality of bottom and side openings 100 which enable entry of fluid from the interior of receptacle 11 into the interior of the housing in order that float 85 may be elevated by the rising fluid surface as the receptacle is being filled. Since fluid exiting through outlet openings 55 can cause undesired fluctuation of float 85, a pair of generally parallel deflectors 101 are attached to the rear, sloping surface of float housing 96 and extend at approximately the same angle as the valve 40. These deflectors channel the fluid away from the float housing and substantially prevent fluctuation of the float 85.

Referring to Fig. 6 an alternative form for venting float chamber 91 is shown, in which a vent tube 105 is slidably attached to opening 92 and extends through the wall of housing 15. The outer end 106 of tube 105 is preferably turned down to discourage the entry of contaminants into the tank as well as to prevent blockage of the outlet opening from ice and the like.

In use, connection to a source of fluid supply is made with outer end 16 of housing 15 and the fluid fed into the interior of housing 15 through tube 31. When the liquid level within receptacle 11 is below the float, the float and float arm will assume the position indicated by the phantom showing in Fig. 1 so that valve member 73 will be canted to open passage 72 to the passage of fluid. When pressure builds up within housing 15 the fluid pressure acting against diaphragm structure 50 will compress coil spring 48 and cause valve seal 47 to move away from valve seat 46, thereby permitting fluid previously kept from chamber 51 by diaphragm structure 50 to flow into the chamber. Once the fluid enters chamber 51 it can of course flow into the interior of receptacle 11 through the plurality of radially disposed outlet openings 55.

During the fluid flow period a small amount of fluid will flow through filtering screen 62, through fluid passage 53, and into chamber 52, and finally into the receptacle 11 through pilot valve 71. Since fluid is leaving chamber 52 as quickly as it is entering there is no build up of pressure behind the diaphragm which would tend to aid coil spring 48 in overcoming the pressure exerted by incoming fluid. Once the level of fluid within receptacle 11 reaches the point where fluid will begin to flow into the float chamber 91, the float 85 will begin to rise and cause movement of connecting arm 87 and actuating arm 74. When the fluid has substantially completely filled the receptacle 11, as shown in Fig. 1, the float will

move upwardly into recess 91 within shield 90, and valve member 73 will seat, and as soon as this occurs, the pressure will rapidly build up behind diaphragm structure 50 until the pressure on both sides of diaphragm 67 will be equalized so that the biasing force of coil spring 48 can seat valve seal 47. During the filling operation, gas which would otherwise be entrapped within the float chamber 91 by the rising liquid level therein is vented by the opening 92 into the passageway 18 in the housing 15, and such vented gas will be entrained with the incoming fluid and carried thereby into the interior of the receptacle 11 for ultimate escape to the atmosphere through the usual tank vent (not shown).

It will also be understood that with the float chamber extending above the upper wall of the receptacle 11, and thereby above the maximum liquid level within the receptacle 11, the float 85 can similarly extend above the upper wall of the receptacle for operation of the pilot valve only when the receptacle is substantially completely filled.

The construction of the float chamber including the vent 92 connecting with the passageway 18 further contributes to efficient operation of the valve, since when the main valve does close and the fluid supply is stopped, whatever small amount of surplus fluid is still present in the passageway 18 above the vent 92 will tend to pass therethrough into the float chamber. The resulting temporary rise of the effective liquid level in the float chamber causes the float to try to rise still higher and thus to assure firm closing of the pilot valve with minimum possibility of fluctuation of the float.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a liquid level control valve for defining the maximum liquid level to be established through an opening in a top wall of a vented receptacle by a high delivery rate source of liquid to fill said receptacle with minimum liquid loss through the air vent of the receptacle, the combination of an inlet housing received on said receptacle over said wall opening and including a portion extending above the level of said top wall and defining an inlet passageway for connection with the fluid delivery source, a valve supporting plate received on said receptacle below said housing, a valve body supported by said plate in depending relation within said receptacle and including means defining an inlet in communication with the interior of said housing to receive the entire flow of fluid from said source and a fluid outlet in communication with the interior of said receptacle, a float-operated pilot valve received in said body, inlet valve means received in said body and controlled by said pilot valve to close said inlet to the further entry of liquid from said source, said plate having a float opening therethrough, an inverted cup-like float shield carried by said plate over said opening and extending into said inlet housing to define a float chamber projecting upwardly into said inlet passageway, means connecting said float chamber to the interior of said receptacle to receive liquid therefrom according to the liquid level in said receptacle, a float received within said chamber and operably connected with said pilot valve to effect operation thereof in response to the liquid level within said chamber, and said shield being proportioned to extend to a level within said inlet passageway substantially higher than the level of said top wall to provide space in said float chamber above the top of the interior of said receptacle in order to provide for complete filling of said receptacle before operation of said pilot valve by said float.

2. The combination defined in claim 1 including means in said shield defining a vent opening into said inlet pas-

sageway for venting entrapped gas from said float chamber into said passageway upon the rise of the liquid level in said chamber due to the filling of said receptacle and also for effecting liquid flow from said passageway into said chamber immediately following closure of said inlet valve means.
